UNITED STATES PATENT OFFICE.

FRED N. LA CHAPELLE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD-FASTENING MACHINE.

1,271,481.

Specification of Letters Patent.

Patented July 2, 1918.

Application filed July 15, 1916. Serial No. 109,473.

To all whom it may concern:

Be it known that I, FRED N. LA CHAPELLE, a citizen of the United States, residing at Beverly, in the county of Essex and State of Massachusetts, have invented certain new and useful Improvements in Thread-Fastening Machines; and I do hereby declare the following to be a full, clear, and exact description of the invention, such as will enable others skilled in the art to which it appertains to make and use the same.

The present invention relates to thread handling machines and more particularly to improvements in machines of this type employed for securing the upper and insole lip of a lasted shoe.

The object of the present invention is to provide mechanism for displacing the toe binding wire to insure the proper location of the toe thread about the toe of the lasted shoe and at one side of the wire, and permit the subsequent removal of the wire without interference with the toe thread.

With this object in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a side elevation of a thread handling machine embodying the present invention; Fig. 2 is a front elevation of the machine shown in Fig. 1; Fig. 3 is a front elevation of the head of the machine shown in Fig. 1; Fig. 4 is a side elevation of the head shown in Fig. 3; Fig. 5 is a detail illustrating a plan view partly in section of the construction for supporting and actuating the channel guide and thread finger; Fig. 6 is a detail illustrating a plan view of the toe wire lifter and back gage in the position which they occupy when passing about the toe of a shoe; and Fig. 7 is a detail illustrating a view of the toe wire lifter in operative relation to the shoe showing the relative vertical positions of the toe wire and toe thread.

The illustrated embodiment of the present invention is shown in connection with the thread handling machine disclosed in

the patent to La Chapelle No. 1,185,108, dated May 30, 1916. This machine is arranged to insert a plurality of individual unconnected thread fasteners through the upper and insole lip of a lasted shoe to retain the shoe in its lasted condition and permit the removal of the lasting tacks prior to the welting operation. The thread fastening machine comprises a curved needle 1 operated from a needle actuating lever 2 through suitable connections to pass two separated loops of thread through the work, mechanism being provided for imparting a rectilinear feeding movement to the needle between the passage of each loop of thread through the work comprising a peripheral cam indicated at 5 and connected to a movable head 6 through the usual cam roll. The work is held during the formation and insertion of the thread fastener by a channel guide 7 and a cooperating back gage 8 engaging respectively in the channel of the shoe and with the outside of the upper. The channel guide is normally held stationary during the operation of the machine and the back gage is moved toward the channel guide in the usual manner to engage with the shoe and is then locked in the advanced position to clamp the shoe firmly. The first loop of thread is engaged by a thread finger 9 supported upon a head 10 to which a rectilinear movement is imparted at predetermined intervals to pass the first loop of thread through the second. During the normal operation of the machine the supply thread is severed at the completion of the thread fastening by a thread cutting knife 12 pivoted upon the back gage and operating to shear the thread against the slot in the back gage. The thread cutting knife is normally operated through an actuating member indicated at 13 which may be moved into an inoperative position to prevent the cutting of the thread when it is desired to bind in the toe of the shoe with a thread passed about the toe and connected at its opposite ends by thread fasteners. This mechanism is clearly shown and described in the patent above referred to and in consequence has been only briefly described herein.

The toe of the lasted shoe is preferably secured by a thread which passes about the

toe and is secured at its opposite ends by thread fasteners located at opposite sides of the toe of the shoe. This toe thread securely binds the toe of the shoe in place and permits the removal of the usual toe wire and anchor tacks which hold opposite ends of the wire. It is desirable to provide mechanism for insuring that the toe thread shall be located entirely at one side of the toe wire in order to permit the convenient removal of the toe wire and anchor tacks at the completion of the thread fastening operation without liability of removing the toe thread therewith. To this end the present invention contemplates the provision of a wire lifting member which is moved into an operative position when passing the thread about the toe of the shoe and is arranged to lift the wire, permitting the toe thread to be located at one side of the wire. The wire lifting member is employed in connection with the back gage to form two points of support which serve as guides for the shoe when turning about the toe. The wire lifting member comprises a roll having an upwardly inclined peripheral face which serves to engage beneath and lift the toe wire when the shoe is pressed against the roll, as shown clearly in the drawings. In the illustrated embodiment of the invention a roll 20 is supported upon the outer end of a curved arm 22 adjustably secured to a slide 23 through the usual bolt and slot connections indicated at 24. The slide 23 is supported in an inclined head 26 secured to the machine frame and is arranged to move toward and from the shoe, as shown clearly in the drawings. The wire lifting member is preferably moved into an operative position after the machine has stopped and while passing the thread about the toe of the shoe. To this end the slide 23 is actuated through mechanism under the control of the operator. The slide is connected with an actuating rod 27 through an arm 28 secured to a rock shaft 30 having a second arm 31 secured thereto and connected with the rear end of the slide 23 through a short link 33. The rod 27 is preferably connected with a knee actuated lever 35 pivoted upon the lower portion of the machine frame at 36 and connected to the lower end of the rod 27, as shown clearly in the drawings. The actuating lever 35 is conveniently provided with a pad 37 supported at the upper end of the lever and having provision for horizontal and vertical adjustments as indicated respectively at 38 and 39. The actuating lever is normally retained in the position shown in Fig. 1 of the drawings through a spring 40 and it will be noted that upon moving the lever in a direction to depress the rod 27 the arm 31 will be swung downwardly, advancing the slide 23 through the link 33 and moving the roll into the position shown

substantially in Fig. 6. In this position the roll and back gage form co-operating work supporting and guiding members against which the shoe is firmly pressed when passing a thread about the toe. As shown clearly in Figs. 6 and 7 of the drawings the position of the roll with relation to the shoe causes the roll to engage beneath and gradually lift the toe wire as the roll progresses about the toe of the shoe. In order to aid in the positioning of the toe thread and insure that the toe thread shall lie closely against the upper, the roll 20 is provided with a tapered under face 42 which serves to separate the toe wire indicated at 43 and the toe thread indicated at 45 in Fig. 7 of the drawings, but presses upon the toe thread, causing it to lie closely against the upper and substantially in the groove in the upper previously occupied by the toe wire. 85

In this type of machine the work is firmly clamped between the back gage and channel guide during the formation and insertion of the thread fastening and at the completion of the thread fastening the back gage is retracted to permit the convenient removal of the shoe. In order to permit the convenient turning of the shoe when threading the toe, however, it is desirable to increase the effective space in which the shoe may be turned. To this end, mechanism is provided for imparting an outward movement of separation to the channel guide and thread finger. In the simplest and most efficient form of the invention which has yet been devised the channel guide and thread finger are connected with the mechanism for operating the wire lifting roll and are automatically moved outward upon a movement of the roll into operative position. To this end the channel guide 7 is secured to the lower end of an arm 47 having a forked upper end 48 pivoted upon a guide rod 50, as shown clearly in Fig. 5 of the drawings. The arm 47 is provided with a second arm 51 extending upwardly therefrom and connected with an arm 52 which is connected at its opposite end to the operating rod 27. The arms 28 and 52 together form a toggle lever which is broken by the rod 27 to simultaneously actuate the wire lifting roll and channel guide and serves to lock the channel guide in operative position when the wire lifting roll is inoperative. To this end, as shown clearly in Fig. 4 of the drawings, the inner ends of the arms 28 and 52 are provided respectively with depending lugs 53 and 54 which engage with one another when the two arms of the toggle lever have moved beyond an aligned position, positively locking the channel guide against movement in either direction. The thread finger 9 is mounted upon the head 10 which is slidably supported upon parallel guide rods 60 and 61. The thread finger is secured to the 130

lower end of an inclined arm 62 pivotally supported at its upper end upon the guide rod 61 and forked to embrace the lower portion of the head 10, as shown clearly in Figs. 3 and 5 of the drawings. The arm 62 is operatively connected with the slide 23 through a rearwardly extending arm 65 projecting from the upper end of the arm 62 and having a slot 66 formed in its lower end which receives a slide block 67 pivoted upon an upstanding lug 68 formed upon the slide 23, as shown clearly in Figs. 4 and 5. With this construction it will be noted that the advancing movement of the slide 23 serves to swing the arm 62 and thread finger outwardly with the channel guide. The thread finger is returned to its initial position by a spring 70 connecting the arm 65 with the frame of the machine. With this construction the rectilinear movement of the thread finger during the formation of the thread fastener merely causes a relative lateral movement of the arm 65 and slide block 67 received therein without breaking the operative connection.

The preferred mode of operation of the improved construction is as follows: A thread fastener is inserted at one side of the toe in proximity to one of the anchor tacks, the thread cutting mechanism having been previously rendered inoperative to prevent the severing of the thread. At the completion of the thread fastening the shoe is released by the rearward movement of the back gage and the operator then actuates the lever 35, moving the toe wire lifting member into operative position, and the channel guide and finger outwardly to permit the turning of the shoe. The shoe is then pressed firmly against the back gage 8 and roll 20 and turned upon these two members to lay the thread against the upper. As the turning of the shoe about the toe progresses the roll 20 engaging beneath the toe wire lifts the wire and causes the toe thread to lie closely to the upper in substantially the position previously occupied by the wire. When the thread has been completely passed about the toe the actuating lever 35 is released and the starting treadle of the machine depressed to clamp the shoe in position and insert a second thread fastener which serves to secure the toe thread in place.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

65 1. A machine for inserting thread fas-

teners through the upper and insole lip of a lasted shoe, having in combination, work positioning devices, thread fastener forming and inserting devices, and means operating to engage with and displace a toe wire to permit a thread to be laid substantially in the groove formerly occupied by the toe wire.

2. A machine for inserting thread fasteners through the upper and insole lip of a lasted shoe, having in combination, work positioning devices, thread fastener forming and inserting devices, a toe wire engaging member, and actuating mechanism for causing the member to engage with and displace the toe wire.

3. A machine for inserting thread fasteners through the upper and insole lip of a lasted shoe, having in combination, work positioning devices, thread fastener forming and inserting devices, a toe wire lifting member, and mechanism under the control of the operator for moving the member into an operative position to engage with and lift the toe wire.

4. A machine for inserting thread fasteners through the upper and insole lip of a lasted shoe, having in combination, thread fastener forming and inserting devices, a back gage and a channel guide co-operating to position the shoe, a toe wire lifting member, and mechanism for actuating the member to cause the latter to engage with the shoe in advance of the back gage to displace the toe wire.

5. A machine for inserting thread fasteners through the upper and insole lip of a lasted shoe, having in combination, a channel guide and a back gage co-operating to position the shoe, thread fastener forming and inserting devices, a toe wire lifting member, and mechanism for moving the member into an operative position and for imparting a relative movement of separation to the channel guide and back gage.

6. A machine for inserting thread fasteners through the upper and insole lip of a lasted shoe, having in combination, a channel guide, a back gage co-operating to position the shoe, thread fastener forming and inserting devices, a toe wire lifting member, mechanism for actuating the member, and connections between the actuating mechanism and channel guide for moving the channel guide away from the back gage when the toe wire lifting member is moved into an operative position.

7. A machine for inserting thread fasteners through the upper and insole lip of a lasted shoe, having in combination, work positioning devices, thread fastener forming and inserting devices, a toe wire lifting roll having an inclined peripheral face, and mechanism for moving the roll into an operative position.

8. A machine for inserting thread fasteners through the upper and insole lip of a lasted shoe, having in combination, work positioning devices, thread fastener forming and inserting devices, a toe wire displacing roll having oppositely inclined peripheral faces, and mechanism for moving the roll in an operative position into engagement with the shoe.
10. 9. A thread handling machine, comprising work positioning devices, thread fastener forming and inserting devices, a toe wire lifting member, and means under the control of the operator for moving the member into an operative position.
10. 9. A machine for inserting thread fasteners through the upper and insole lip of a lasted shoe, having in combination, thread fastener forming and inserting de-
- 20 vices, a back gage, a channel guide pivoted for movement toward and from the back gage, a toe wire lifting member, and means under the control of the operator for simultaneously moving the toe wire lifting member inwardly toward the shoe and for swinging the channel guide outwardly away from the back gage.
11. A thread handling machine, having in combination, thread fastener forming and inserting devices, a back gage, a channel guide pivoted for movement toward and from the back gage, a toe wire lifting member, a toggle lever connected with the channel guide, connections between the toggle lever and toe wire lifting member, and means under the control of the operator for actuating the toggle lever.
